Inventor

Frederick B. A. Kirsten,

UNITED STATES PATENT OFFICE

FREDERICK B. A. KIRSTEN, OF MASON CITY, IOWA

SOFT-COLLAR SUPPORT

Application filed July 25, 1927. Serial No. 208,254.

This invention relates to improvements in wearing apparel and has for its object to provide a soft collar having means whereby the collar will be held in upright position.

5 A further object of the invention is to provide in a soft collar, means for preventing the collapse thereof through wilting or other causes.

A still further object of the invention is 10 to provide in a soft collar a movable, semi-rigid supporting band, for holding the collar against collapse and means for holding the band extended said means being adapted to hold a tie form.

15 With the above and such other objects in view as may hereinafter more fully appear I have invented the device shown in the accompanying illustration, in which:

Figure 1 is a front elevational view of my 20 improved collar;

Figure 2 is a back view of the collar shown unfolded and extended;

Figure 3 is a section on line 3—3 of Figure 2;

25 Figure 4 is a detail perspective view of a stiffener member removed from the collar;

Figure 5 is a section on line 5—5 of Figure 2;

30 Figure 6 is a side elevational view of a collar, embracing my invention.

Like reference characters indicate like parts throughout the following specification and in the several views in the drawings in which 6 indicates a soft collar having an 35 outer fold 7, and an inner fold 8 in which latter fold is provided two longitudinal pockets 9 and 10 slightly spaced apart at the central rear portion 11 of the collar and having opposing openings 12 and 13' for 40 said pockets. Removably seated in said pockets and extending substantially throughout the entire length of the fold 7, is a stiffener member 13, formed preferably of celluloid or some other similar semi-rigid strip which is provided throughout its 45 length with perforations 14 to permit the passage of air through the strip in order that perspiration on the collar may be caused to quickly evaporate. The band 13 is removable for laundering purposes.

The member 13 is provided with buttons 15 and 15' adjacent its ends 16 and 17 which are adapted to project through button holes 18 and 19 formed in the walls 20 and 21 of the pockets 9 and 10 adjacent their outer 55 ends, said buttons being adapted to hold the member 13 extended and prevent undue coiling thereof said buttons being also adapted to engage the eyes 22 and 23 of the tie form 24, upon which a tie (not shown) may be 60 formed. The members 9 and 10 carry loops 25 and 26, adjacent said button holes 18 and 19, said loops being adapted to loop over the buttons 15 and 15' after the tie form 24, has been buttoned thereon, so as to prevent 65 accidental relative displacement of said members. It is obvious from the above description that a collar made according to my invention will be held in an upright position and be prevented from collapsing 70 through moisture of perspiration, or the inability of the flexible material from which it is formed to stand up.

Having described my invention that which I claim to be new and desire to procure by 75 Letters Patent is:

1. In combination with a collar having a neck band fold provided with longitudinal pockets intermediate the ends thereof, a stiffener adapted to be seated substantially entirely within said pockets, said stiffener having buttons thereon adapted to project through button holes in said pocket members whereby the stiffener will be held against 80 curling.

2. The combination set forth in claim 1, and a link tie form for connecting said buttons.

3. The combination set forth in claim 1, and a tie form for connecting said buttons, 90 said tie form having button holes at each end.

4. The combination set forth in claim 1, and a link for connecting said buttons, said link having button holes at each end, through 95 which said buttons are adapted to project, and loops attached to said pocket members to overlie said link and engage the outer end of said buttons to prevent displacement of said link from said buttons.

5. In a turned down collar an inner fold having pockets formed between the inner and outer layers of said fold and substantially throughout the length of said fold, a stiffener having buttons fixed adjacent its ends adapted to be seated in said pockets, said inner layers having independent button holes through which said buttons are adapted to project and the outer fold adapted to overlie said buttons.
10. 6. The combination set forth in claim 5, and means for connecting said buttons around the neck of the wearer whereby said stiffener will be maintained in operative position to stiffen said collar.
15. In testimony whereof I affix my signature.

FREDERICK B. A. KIRSTEN.
